UNITED STATES PATENT OFFICE.

JOHN D. BOLEY AND HARRY K. FAIRALL, OF HIGHLAND, CALIFORNIA.

HYDROCARBON-BURNING APPARATUS.

1,117,773.

Specification of Letters Patent.

Patented Nov. 17, 1914.

Application filed May 19, 1913. Serial No. 763,672.

To all whom it may concern:

Be it known that we, JOHN D. BOLEY and HARRY K. FAIRALL both citizens of the United States, residing at Highland, in the 5 county of San Bernardino and State of California, have invented a new and useful Hydrocarbon-Burning Apparatus, of which the following is a specification.

An object of this invention is to provide 10 means that will burn petroleum of low gravity, such as the petroleums known as crude oils and distillates, with maximum efficiency, cleanliness, economy, convenience, and safety, and without odor.

15 Further objects are automatic regulation of the fire, the production of a large volume of blue flame in stove, furnace, fireplace or the open air; to avoid accumulations of unconsumed products which might clog the 20 burner; and also to provide a construction of burner which is not liable to clog.

It is well-known that low grade petroleums can be burned to the best advantage by 25 the use of an atomizing or nebulizing fluid, such as air or steam under pressure, the same being directed to act upon the oil so as to spray, vaporize or nebulize the same; and this invention is designed to provide a self-contained burning apparatus of 30 convenient size which will automatically produce the required steam pressure for a pre-determined amount of fire, which can be easily charged with water and oil and will burn evenly and uniformly after fully starting into operation, until practically all of 35 the water and oil have been consumed.

An object of the invention is to provide 40 a hydrocarbon burner using oil and water to the best advantage as fire-producers and to so construct the apparatus that it may be 45 of convenient size for domestic and household use and other purposes; and also to provide a self-contained pressure-operated oil burning apparatus that can be used in orchards for preventing frost.

The accompanying drawings illustrate the invention.

Figure 1 is a side elevation of a hydrocarbon burning apparatus constructed in accordance with this invention and adapted 50 for use as an orchard heater. Fig. 2 is an enlarged fragmental sectional elevation on line z^2 , Figs. 3, 6 and 7. Fig. 3 is an enlarged fragmental sectional elevation on line x^3 , Figs. 1, 2, 5 and 6. The water level 55 is shown and the arrows indicate the course

of the steam in the generating tubes. Fig. 4 is an elevation of the fuel nozzle and the jet tip. Fig. 5 is a broken elevation of the apparatus as it may be arranged for household use. Fig. 6 is a plan of the apparatus as shown in Fig. 5. Fig. 7 is a broken elevation from the left of Figs. 5 and 6.

It is understood that the apparatus can be variously constructed and that the invention is not limited to the specific forms shown in the drawings.

In this invention we provide a closed circuit comprising a pressure tank 1, lower and upper conduits 2, 3, respectively connected with the pressure tank below and above the liquid level of said tank, and a liquid trap or steam generator 4 connecting said conduits; and we arrange the same in combination with a jet piece 5 connected 70 by pipes 6, 7, with the circuit outside said liquid level and directed toward the trap, and fuel supply means comprising a nozzle 8, valve 9, pipe 10 and oil reservoir 11.

In combination with said closed circuit, 80 jet means 5 and the fuel supply means, there are also provided certain means to direct the jet, certain means to apply the flame to the liquid trap, certain means to distribute the flame, and certain means to mix the fuel 85 with air around the trap so as to secure the highest efficiency; and in this connection various features of construction are employed. That is to say, the jet directing means shown in the drawings is formed at 90 the end of the pipe 6 by constructing the end of the pipe with a spoon-like tip comprising a bowl 12 having an open concaved end 13 in front of a contracted orifice 14 which opens behind and below the nozzle 8, 95 so that when there is no pressure in the pressure tank any oil flowing from said nozzle will be caught in the bowl and held in front of the contracted orifice 14; and when pressure is produced in the tank 100 a blast proceeds from said opening and the oil will be caught by such blast and carried forward toward the trap; and as the operation continues the oil is sprayed, atomized or nebulized and forcibly driven toward the 105 trap.

Said trap is preferably an S-trap constructed of three vertical limbs 15, 16, 17 and suitable bends arranged in a common plane that is normal to the axis of the jet 110 piece 5, the first limb 15 being connected by an elbow 18, nipple 19 and elbow 20 with

the lower conduit 2 of the circuit, and being also connected by bend 21 with the middle limb 16 which in turn is connected by a bend 22 with the discharging limb 17 of the trap that in turn is connected by an elbow 23 with the upper conduit 3 of the circuit.

A pan 24 having a lip 25 arranged below the jet means 5 and the nozzle 8 receives any drip which may occur from the tip 12 and 10 causes the same to accumulate directly below the trap; the bottom of the pan being sloped and centrally concaved for this purpose, and the trap being arranged centrally above the bottom of the pan. Said 15 pan is provided with a wall 26 which prevents the liquid from overflowing and is arranged also to form a seat for a fire chamber 27 that fits within the wall which is preferably made circular throughout a portion 20 of its extent; and said fire chamber is provided with an inlet 28 directly in front of the jet means and between the jet means and the lower bend 22 of the trap, and is also provided with an outlet or open top a 25 above the level of the jet piece, so that when the jet is in operation the liquid fuel from the nozzle 8 will be driven through the inlet 28 to produce fire inside the fire chamber 27 and against the lower portion of the trap. 30 From the foregoing it is clear that flame will be directed against the limb 15 to generate steam therein, and that flame will also be directed against the limbs 16 and 17 to further heat the steam generated in the limb 35 15, thus enabling steam to be quickly raised and also insuring maximum steam pressure with minimum consumption of fuel so that a small fire will produce relatively high steam pressure to effect substantially perfect 40 combustion.

A perforated mixing plate 29 is held in place inside the fire chamber by lugs 30 below the top of the fire chamber so that the fuel and the air carried by the jet into the 45 fire chamber may become thoroughly mixed so as to burn in the most efficient manner, the result being that the main combustion, will take place above the mixing plate, and practically complete combustion will occur 50 above said plate when the burner is in operation.

The pipes 6, 7 are provided with a safety valve 31 which will be set to blow off at a desired pressure.

55 The degree of combustion depends upon the force of the jet and the amount of liquid fuel supplied thereto; the force of the jet depends upon the amount of heat applied to the trap, and the amount of heat applied 60 to the trap will depend upon the amount of fuel supplied to the burner.

A water glass 32 is provided to indicate the amount of water contained in the pressure tank which is adapted to be filled 65 through the filling port 33 that is ordinarily

closed by a plug 34; and in the form shown in Fig. 1, the oil reservoir 11 is located immediately above the pressure tank 1, the walls of the tank and reservoir being constructed of one piece of sheet metal, there 70 being a bottom or partition 35 between the upper and lower ends of said wall, the bottom 36 of the pressure tank being fastened in the lower end and the bottom 35 of the oil reservoir being fastened intermediate the 75 ends of said wall. The oil reservoir may be provided with a loose cover 37 which may be removed and replaced as desired. It is understood, however, that the tank and reservoir as well as other parts of the apparatus 80 may be of cast metal or may be of any suitable construction.

In practice the pressure tank 1 is filled with water to a level below the upper conduit 3, thus filling the lower conduit 2 and 85 the first limb 15 of the trap to a desired level, but leaving the middle and discharge limbs 16, 17, the bend 22, elbow 23 and upper conduit 2 free from water. The oil reservoir will be supplied with oil and when 90 it is desired to start the burner into operation, the valve 9 will be opened to allow oil to drip through the nozzle 8, thus to fill and overflow the bowl of the burner tip. The overflow oil will be caught by the lip 25 and 95 directed into the pan 24 where it may be ignited by a torch or any other suitable means, whereupon the flame rises therefrom around the trap, heating the same and thus generating steam which passes through the upper 100 bend 21, the middle limb 16, lower bend 22, the discharge limb 17 and the upper conduit 3 into the upper portion of the pressure tank from which the pressure is applied through the pipes 7 and 6 to the jet piece 5, thus acting 105 upon the fuel that drips from the nozzle 8 and spraying the same through the inlet 28 into the fire chamber where the fuel becomes ignited and increases the heat upon the trap, thus increasing the production of 110 steam and increasing the pressure in the pressure tank and at the jet piece 5, so that the fire in the fire chamber is intensified. The amount of fire will be regulated by opening or closing the valve 9, thus to allow 115 a greater or less amount of oil to escape through the nozzle 8. When the burner has come into complete operation, the amount of fire will practically remain invariable so long as the amount of oil delivered through 120 the nozzle 8 remains unchanged. The heat is applied directly to the intermediate and discharging limbs and tends to directly heat the steam that flows to the jet piece.

It is desirable that the steam delivered at 125 the jet piece shall be wet and therefore high pressures are not required. By arranging the oil tank above the pressure tank, as shown, the heat from the steam in the pressure tank tends to keep the oil in a high state of 130

fluidity, thus facilitating combustion and enabling the burner to burn heavy oil with ease.

With the form shown in Fig. 1, the whole apparatus, excepting the pan 24 and the fire chamber and mixing plate, is fixed together and can be conveniently carried into the orchard and changed from place to place. The fire chamber and mixing plate will be connected to the conduits 2, 3; and the pan may be separately carried. In the drawings the pressure tank and the pan are shown supplied with legs 38, 39, but it is understood that many variations of construction and arrangement may be made without departing from the spirit of this invention. When assembled the pan 24 supports the fire chamber and the legs 39 support the pan.

In the modification shown in Figs. 5, 6 and 7, the oil reservoir 11 is not directly above the pressure tank 1 but is separately supported, so that it may be situated in any place outside of the house which may be desirable when the device is used for household purposes. In this modification, the filling port 33 and closing plug 34 are situated in the top of the pressure tank 1, and the safety valve 31 extends above the top of the pressure tank 1.

The nozzle 8 is formed of an elbow screwed onto a nipple 81 that is screwed into the body of the valve 9 in front of the valve seat 40 that is closed by the needle 41, and the bore of the elbow is circular and of large diameter as compared with that of the nipple, so that there will always be plenty of air space above and in front of the stream of oil that flows from the nipple, and said oil stream is accommodated at the rear segment 42 of said bore and the front wall of the elbow is cut away obliquely as shown at 43 to bring the tip of the nozzle to a central point at the rear of the nozzle so that the oil will flow down in a fine true stream directly onto the center of the steam jet that issues from the jet orifice. The top of jet pipe 6 is flattened and slanted downward at the portion 42 just behind the jet orifice 14, thus to direct the steam jet downward toward the upwardly slanting front portion at 13, of the tip, thus to break up the steam jet by glancing impact on the tip. By this construction and arrangement of the nozzle and jet piece, the moderate pressures involved, operate with great efficiency to put the oil and air into the fire chamber in proper condition for combustion.

By this construction and arrangement the safety valve 31 may be set to blow off at a pressure of from 5 to 15 pounds, thus insuring safety against explosions.

The nozzle 8 is held in place relative to the jet-piece 5 by suitable means as the clamp shown which consists of a bent plate

44 embracing the nozzle nipple 81, and the jet-piece pipe 6 and sprung tightly thereon by the bolts and nuts 45.

The plate 29 may be formed of two pieces as shown in Figs. 2 and 6 so as to be easily put into and removed from around the trap in the fire chamber.

We claim:—

1. In an oil-burning apparatus, the combination of a closed circuit comprising conduits and a tank adapted to contain water, a fire chamber situated to supply heat to a portion of said conduits whereby the water entering said conduits from said tank will give off steam which will return to the tank above the water supply, an oil reservoir situated directly above said tank whereby the heat of the steam in said tank will heat the oil to increase its fluidity, a jet piece directed into said fire chamber, a pipe connecting the upper end of said tank to said jet piece to supply steam thereto, a nozzle situated above said jet piece, and a pipe connecting said oil reservoir to said nozzle to supply oil thereto, said nozzle being positioned to drip oil onto said jet piece. 75

2. In an oil-burning apparatus, the combination of a closed circuit comprising conduits and a tank adapted to contain water, a fire chamber situated to supply heat to a portion of said conduits whereby the water entering said conduits from said tank will give off steam which will return to the tank above the water supply, a partition forming the top of said tank, an oil reservoir situated directly above said tank whereby the heat of the steam in the tank will heat the oil to increase its fluidity, said partition forming the bottom of said oil reservoir, a jet piece directed into said fire chamber, a pipe connecting the upper end of said tank to said jet piece to supply steam thereto, a nozzle situated above said jet piece, and a pipe connecting the oil reservoir to said nozzle to supply oil thereto, said nozzle being 90 positioned to drip oil onto said jet piece. 95

3. The combination with a closed circuit comprising a pressure tank, lower and upper conduits connected with the pressure tank below and above the liquid level of said tank, and a trap connected with said conduits; of a fuel supply reservoir, jet means connected with the circuit above the liquid level and directed toward the trap, a fuel supply pipe connected with the fuel supply 115 reservoir and directed to supply liquid fuel to said jet means, a fire chamber surrounding the trap and provided with an orifice to admit a jet to the trap from said jet means, said fire chamber having an outlet above 120 the level of the jet, and a perforated mixing plate in the chamber below the outlet and above the level of the jet means. 125

4. In an oil-burning apparatus, the combination of a closed circuit comprising con- 130

duits and a tank adapted to contain water, a fire chamber situated to supply heat to a portion of said conduits whereby the water entering said conduits from said tank will give off steam which will return to the tank above the water supply to there increase the pressure in said tank, an oil reservoir, a jet piece directed into said fire chamber, a pipe connecting the upper end of said tank to 10 said jet piece to supply steam thereto, a nozzle situated above said jet piece, and a second pipe connecting the oil reservoir to said nozzle to supply oil thereto, said nozzle being positioned to drip oil onto said jet piece.

15 5. In an oil-burning apparatus, the combination of a closed circuit comprising conduits and a tank adapted to contain water, means to heat the water while passing from one conduit to the other conduit whereby 20 the water entering said conduits from said tank will give off steam which will return to the tank above the water supply, an oil reservoir, a burner, a pipe in communication with the upper end of said tank to conduct steam to said burner, and a second pipe in communication with the oil reservoir to conduct oil to said burner.

25 6. The combination with a fuel nozzle and jet-piece, of a liquid trap having vertical 30 limbs arranged in a common plane that is normal to the axis of said jet-piece, and means to maintain water in one of said limbs, said jet-piece when lighted being directed toward the limbs to heat the same so

that steam rises from the water in said one limb and passes over into the succeeding vertical limbs to be there further heated. 35

7. The combination of a closed circuit comprising a pressure tank containing water, a liquid trap, said trap having three upright limbs, a conduit connecting the upper end of the pressure tank with the upper end of one of the outer limbs of said trap, a second conduit in communication with the lower end of the tank and passing under the three limbs and connected to the lower end of the other outer limb, jet means connected with the pressure tank and directed toward the lower ends of the three limbs of said trap and the portion of the conduit passing under said limbs, and fuel supply means to supply liquid fuel to said jet means, water being maintained in said other limb at a level equal to the water level in said tank, the jet means when lighted heating the water in said other limb thereby forming steam which rises and passes to the succeeding limbs where it is further heated before returning to the tank. 40 45 50 55

In testimony whereof, we have hereunto set our hands at Highland, California, this 12th day of May, 1913.
